UNITED STATES PATENT OFFICE.

EDWIN M. BASSLER, OF MILWAUKEE, WISCONSIN, ASSIGNOR TO BAYLEY MANUFACTURING COMPANY, OF MILWAUKEE, WISCONSIN, A CORPORATION OF WISCONSIN.

HEATING APPARATUS.

1,226,298.

Specification of Letters Patent.

Patented May 15, 1917.

Application filed September 3, 1914. Serial No. 859,997.

To all whom it may concern:

Be it known that I, EDWIN M. BASSLER, a citizen of the United States, and a resident of Milwaukee, in the county of Milwaukee and State of Wisconsin, have invented a certain new and useful Improvement in Heating Apparatus, of which the following is a specification.

This invention relates to heat generators and radiators, and relates particularly to generators and radiators designed and adapted for use in connection with systems or apparatus for hot air heating and ventilating by forced circulation.

15 The principal objects of the invention are to increase the efficiency of the heat generating and radiating apparatus; to simplify the construction and reduce the cost thereof; to provide a heat generating and radiating apparatus which shall be relatively small, compact and self contained; to prevent loss of heat by radiation; to obviate danger from explosions; and to provide a generator and radiator which may be operated without an expert engineer and with a minimum of work and attention.

Considered broadly, I effect the foregoing objects by combining a generator with a radiator so as to form a unitary structure and in such manner that the heating medium will pass directly from the generator to the radiator, thus dispensing with all pipe connections between said generator and radiator, and also maintaining this heating medium practically at its maximum temperature, so that, when it is returned to the generator, but very little heat will be required to again convert it into steam. Specifically said invention consists of the various features, combinations of features and details of construction hereinafter described and claimed.

In the accompanying drawings, in which my invention is fully illustrated,

25 Figure 1 is a side elevation of a combined steam generator, radiator and blower, illustrating the application of my improved apparatus for hot air heating by forced draft or circulation.

50 Fig. 2 is a central, vertical, longitudinal section thereof.

Fig. 3 is a sectional elevation thereof on the line 3—3 of Fig. 2.

55 Fig. 4 is a sectional elevation on the line 4—4 of Fig. 2.

Fig. 5 is a top plan view partly in section, of a unit section of my improved generator and radiator; and

Fig. 6 is an enlarged fragmentary detail sectional view on the line 6—6 of Fig. 4.

Referring now to the drawings, in which I have shown what I now consider to be the preferable embodiment of my invention and preferable means for applying same for use in a system of hot air heating and ventilating by forced circulation, I will first describe in detail the construction of the generator and radiator and will then describe the setting therefor and the manner of applying same for use.

The body portion of my improved generator and radiator, designated as a whole A, is hollow and comprises legs or sections A', A² which extend substantially at right angles to each other. Said body portion will 75 hereinafter be referred to as a header.

The interior of said header A is divided into compartments by means of a partition comprising sections A³, A⁴ in the legs A', A², respectively. From the point of juncture of 80 the sections of said partition, the partition section A⁴ is continuous to the end of the horizontal leg A² of the header, while the section A³ preferably terminates about two inches short of the lower end of the vertical leg A' of said header, thus permitting the water columns on opposite sides of said partition A³ to equalize and also providing for draining the said body portion, when desired.

For convenient reference the compartments in the leg A' formed by the partition A³ are designated, respectively, a, a' and the compartments formed in the leg A² by the partition A⁴ are designated, respectively, 95 a², a³.

Secured to the wall 1 of the leg A' are tubes 2, the inner ends of which are in open communication with the compartment a of said section A' and the outer ends of which 100 are closed; and secured in the partition section A³ are tubes 3, said tubes 3 being smaller than the inside diameter of the tubes 2 and extending into said tubes, and being preferably of such length that they will extend to within a short distance of the closed outer ends of said tubes 2. Both ends of the tubes 3 are open, said tubes thus connecting the compartment a' of the leg A' with the interiors of the tubes 2 adjacent to their closed 110

ends, and through said tubes with the compartment α of said header leg A'.

The pipes 2 are of proper size to provide adequate heating surface and to produce a desired velocity of water circulation therein to secure efficient and economic operating conditions. Also, I preferably use relatively large tubes at the extreme front end of the generator where the heat is most intense, said relatively large tubes being designated 2' in the drawing and the tubes which extend inside thereof 3'. For ordinary uses, desirable sizes of tubes are about 2 inches for the tubes 2' and $\frac{3}{4}$ of an inch for the tubes 3', and $1\frac{1}{4}$ inches for the tubes 2 and $\frac{1}{2}$ of an inch for the tubes 3.

The tubes 2, 2' extend beneath the leg A² of the header A and are of such length that they will terminate slightly short of the end of said leg.

In like manner, tubes 4 are secured in the upper wall 5 of the leg A² of the header A, the inner ends of said tubes being in open communication with the compartments α^2 of said body portion and the outer ends thereof being closed; and secured in the section A⁴ of the partition wall are tubes 6 both ends of which are open and which connect the compartment α^2 of the leg A² with the interiors of the pipes or tubes 4 adjacent to their closed outer ends.

For convenience and economy in constructing different sizes of generators and radiators embodying my invention, I preferably make my improved generator and radiator in the form of similar separate units, any number of which may be connected together, in the relation shown in Fig. 1, to form a generator and radiator of any desired size. I do not desire to limit myself to this construction, however, as my invention contemplates the use of headers made in one piece regardless of their size.

The preceding description has particular reference to a single unit and applies equally to all of the units and I shall therefore apply the reference letter A to designate the body portion of each unit as well as of the entire structure, which may consist of a single unit or of a plurality of units.

In the preferable construction shown, the units A are connected to form a unitary structure by bolts 7, the nuts threaded to the ends of which afford convenient means for drawing said unit sections into close contact with each other and to provide for equalizing the water level and the steam pressure in the different units, said units are connected so as to communicate with each other both above and below the designed water level therein. As shown, see particularly Fig. 6, said units are connected by means of nipples 8, the ends of which are slightly tapered and which are adapted to be forced or drawn into tight engagement

with corresponding tapered seats formed in openings 9 in the adjacent walls of said generator units. In the preferable construction shown, three bolts 7 are employed and the headers A of the generator units are provided with three sets of openings 9, the holes of each series being arranged in alinement with each other, thus forming a continuous hole from end to end of the generator through which the connecting bolts 7 extend, and the nipples 8 being enough larger than the bolts 7 to form communicating openings of desired size between the different units. In ordinary practice, I use $\frac{3}{4}$ " bolts and 3" i. d. nipples. Also, the joints between the different units are sealed with cement which will harden under heat, thus preventing the products of combustion, smoke, gases, etc., from passing from the combustion chamber of the furnace to the inclosed space which contains the heating tubes, as will presently appear.

In setting my improved generator and radiator, the leg A' is disposed vertically and the leg A² horizontally, the pipes 2, 2' extending horizontally beneath the leg or section A² and the pipes 4 extending vertically from the upper side of said leg or section A².

While my invention contemplates any suitable setting for my improved generator and radiator, I prefer the setting shown in the drawings, which I will now describe. The lower end of the header leg A' rests directly on the foundation and forms part of the side wall of the furnace setting. The outer end of the horizontal leg A² is supported by a plurality of plates or panels 10 the lower ends of which rest on the foundation and the upper ends of which are inserted beneath a rigid part formed by separate flanges on the outer end of each unit section A and said plates or panels are connected together and to the header by bolts inserted through flanges 12 formed at the margins of said plates or panels 10 and through the flanges or brackets 11 on said header and the flanges 12 on the upper edges of said plates or panels. The setting walls are extended forward and a short distance rearward from the generator, both lateral walls thereof being formed by plates or panels similar to the plates or panels 10 and secured to each other in the same manner, and the top thereof is formed by arched plates 13, of the same width as the plates or panels 10 and which comprise end sections 14 which extend downwardly from the main parts of said arched plates on substantially radial lines. Like the side plates or panels 10, the top plates 13 are adapted to be secured to each other and to the upper ends of the side panels and to the walls of the end generator and radiator units A by means of cap screws or bolts inserted through

flanges 15 formed entirely around the edges of said top plates 13 and, at the ends, through the flanges 12 on the upper edges of said side plates or panels. The front 5 and back top plates adjacent to the extreme front and back heater units A are secured directly thereto by cap screws inserted through the flanges 15 on adjacent edges of said top plates and which are threaded into 10 suitable screw threaded holes formed in the wall of the header.

The front of the setting is closed by a front wall 16 provided with usual firebox and ashpit doors and the rear end of said 15 setting is closed by a rear wall 17 provided with a smoke stack opening 18 and adjacent to its bottom with a cleaning door 19.

Said front and rear walls are connected to the adjacent top and side plates by means 20 of bolts or cap screws inserted through the edges thereof and through the marginal flanges on said top and side plates.

The side plates 10, top plates 13 and front and rear walls 16 and 17 are preferably 25 made of cast iron and the joints between adjacent plates are rendered tight by means of suitable cement.

A bridge wall 20 divides the interior of the setting into a usual firebox and combustion chamber and supported within the furnace are usual grate bars 21 on which the fire is supported and beneath which is the ashpit.

The cast iron walls of the setting are projected by means of linings of suitable refractory material. While my invention contemplates the use of any desired or used form of linings, I prefer the form shown, which consists of plates made of fire clay 35 of substantially the same size and shape as the inner side of said side panels and top plates. In the preferable construction shown, the side plates or panels have linings designated 22 which are adapted to be held 40 in position on the inner sides of the side plates or panels 10 in the following manner:

Formed on the lower ends of said side panels are inwardly projecting flanges 23 50 on which the lower ends of the linings 22 rest, the inner ends of said flanges 23 being turned upwardly as shown at 24 to form shoulders or ledges adapted to hold the lower ends of said linings 22 in position on 55 said flanges 23. At their upper ends the lining plates 22 are inwardly and downwardly beveled as shown at 25 and are adapted to interlock with correspondingly inclined surfaces on the linings of the top plates 13 and on the outer ends of the horizontal leg A² of the header A. As shown, 60 the linings for the top plates 13 consist of plates 26 which are curved to correspond with the arches of said top plates 13 and 65 the ends of which fit closely against the in-

clined ends or shoulders 14 of said top plate, whereby said top lining plates will be held in position by means of a dove-tailed connection therewith, see Fig. 4, and also by means of the inclined surface 25 at the outer 70 ends of said plate linings.

To provide for operating my improved generator and radiator by means of forced draft, a chamber 27 is formed in the bridge wall 20, which communicates with the ashpit of the furnace by means of openings 28 in the front side of said bridge wall. Air under pressure is adapted to be admitted to the chamber 27 through an opening 29 formed through the side wall of the generator setting, said openings being preferably provided with a thimble extension 30 for convenience in making pipe connections thereto. As shown, the opening 29 is formed in one of the side plates 10 and in 80 the refractory lining therefor, the thimble 30 being preferably cast integral with said side plate.

My improved generator and radiator will be preferably provided with usual steam 90 and water gages, safety valves, automatic air vents, blow-off cock and automatic damper regulator. These, however, form no part of my present invention and can readily be applied by any skilled mechanic familiar with this line of work.

To provide for observing the interior of the combustion chamber, peep holes indicated generally at 31 and which are adapted to be covered by suitable pivoted shutters 100 designated 32 are provided in the side plates 10 which support the ends of the leg or section A² of the generator.

The heater tubes 4 are inclosed by a suitable casing 33 preferably made of galvanized iron or the like and which is provided at one end with a blower connection 34 and at its opposite end with a discharge opening 35 to which a discharge pipe, not shown, is adapted to be connected.

To provide for tempering the air discharge from the casing 33, said casing is preferably divided longitudinally by a horizontal partition 36 which separates the interior thereof into a chamber 37 in which the heating pipes 4 are located and in a cold air passageway 38, the relative amounts of air passing through the chambers 37 and 38, respectively, being controlled by means of dampers 39 and 40 which control the discharge ends of said chambers or passageways, respectively. In practice said dampers are preferably controlled automatically by suitable means provided for the purpose. Means for this purpose are old and well 115 known and, as they form no part of my invention, and can readily be supplied by persons familiar with the art, such means are not shown in the drawings.

Connected to the admission opening of 130

the casing 33 which incloses the heating tubes 4 is the discharge end of a fan or blower by means of which a forced circulation of air may be maintained through said casing 33 which communicate with the discharge opening of said casing.

In the preferable construction shown, the fan or blower, designated B, is mounted directly on the top of the setting at the front 10 side of the header A of the generator and is adapted to be driven by an electric motor mounted directly upon the fan casing.

While I consider the foregoing arrangement for the fan and blower to be preferable, I do not desire to limit myself thereto, as my invention contemplates supporting the fan in any desired relation to the generator and driving the same in any desired or approved manner.

20 As shown, the chamber 27 in the bridge wall 20 is connected with the fan casing by means of a pipe 41 connected to the opening 29 at one end with a corresponding opening in the fan casing at its opposite 25 end. Said pipe is controlled by means of a suitable slide or damper 42 by which the amount of air supplied to the chamber 27 may be regulated as desired.

The normal water level in the generator 30 is somewhat above the bottom wall of the horizontal leg or section A² of the header A and is indicated in the drawing by the line x—x, Fig. 3.

With the described construction, it is obvious that all of the pipes 2 and 3 and the chambers a, a¹ and a² to the height of the line x—x, will be full of water and will be heated to a high temperature by contact of the fire and products of combustion with 35 the pipes 2, and with the inner wall 1 of the vertical leg and the lower wall of the horizontal leg of the header, all of which are exposed to the direct action of the heat and products of combustion passing from the 40 furnace to the stack opening. As the water is converted into steam, it rises into the chamber a² above the level of the water and passes thence upward through the inner tubes 6 into the upper ends of the heating tubes 4 and is wholly or partially condensed 45 by the current of air from the blower B passing among and around said pipes. As said steam condenses, the water drains from the pipes 4 into the chamber a³, and thence 50 along the partition A⁴ into the chamber a¹ and into the main body of water. From said chamber a¹ the water flows outwardly through the pipes 3 into the outer ends of the pipes 2 and back through the pipes 2 55 into the chamber a, where it is again converted into steam. Due to the fact that the generator has practically no radiating surface excepting the radiator tubes 4, it is obvious that the condensed water which drains 60 into the chamber a¹ will be only slightly be-

low the temperature at which it will pass into steam and that only a very small quantity of heat will be required to again convert said water into steam. At the same time, the steam from the chamber a² will be delivered into the heating pipes 4 practically 70 without loss of heat from outside radiation. Thus, after the water in the generator has been once heated to the point at which it is converted into steam, comparatively a very 75 small quantity of fuel will be required for maintaining a supply of steam and, owing to the fact that there is practically no loss of heat by radiation in the passage of the steam from the generator to the radiator, the 80 air passing through the casing 33 will be heated to the highest possible degree, thereby resulting in the highest possible efficiency 85 and economy in the operation of the apparatus.

In addition to its very high efficiency, my improved generator and radiator possesses important advantages over any system of heating by forced circulation of air of which I have any knowledge in the respect that all 90 piping and fittings heretofore necessary for connecting a boiler with the heating coils are dispensed with, thus effecting a material saving both in material and labor and also very greatly reducing the space occupied by 95 the separate boilers, heating coils, blowers and motors as heretofore used. Moreover, the operation of my improved generator and radiator requires the attention of an operator merely for stoking the furnace at intervals as may be necessary, all other functions 100 of the generator being automatic and self adjusting.

While I consider the form of my improved generator and radiator herein shown and described as being the preferable embodiment of my invention, it is possible that in view of my disclosure, other forms of apparatus could be readily devised by skilled mechanics for carrying out my said invention and I 105 do not therefore, desire to limit myself to the exact form of apparatus herein shown and described, but desire to include all forms 110 of apparatus by which my said invention may be carried out.

I claim:—

1. The combination of a generator and radiator comprising a header, a partition which divides the interior thereof into compartments, pipes secured in said header the 120 inner ends of which are in open communication with the interior of said header and the outer ends of which are closed, said pipes including generator and radiator pipes which communicate, respectively, with different compartments of said header, open-ended pipes secured in the partition wall and which extend into the pipes secured in said header, the attached ends of which are in open communication with the compart- 125 130

- ments of the header other than those with which the pipes into which they extend, respectively, communicate, a furnace setting for said header which incloses the generator pipes which communicate with one compartment of said header, and a casing which incloses the radiator pipes which communicate with the other compartment of the header, said casing being provided with an admission opening adapted for connection with a blower and with a discharge opening adapted for connection with a heating and ventilating system, substantially as described.
- 15 2. The combination of a generator and radiator comprising a header comprising a substantially vertical leg, and a substantially horizontal leg, a partition which divides the interior of said header into compartments, generator pipes secured in the vertical leg of said header and which extend beneath the horizontal leg thereof and which communicate with one compartment of said header, and radiator pipes secured in the horizontal section of said header, the inner ends of which communicate with the other compartment of said header and the outer ends of all of said pipes being closed, open-ended pipes secured in the partition wall and which extend into the pipes secured in said header and which communicate with the compartments of the header other than those with which the outer pipes into which they extend, respectively, communicate, a furnace setting for said header which incloses the generator pipes secured in the vertical leg or section of the header, and a casing which incloses the radiator pipes secured in the horizontal leg or section of the header, said casing being provided with an admission opening adapted for connection with a blower and with a discharge opening adapted for connection with a heating and ventilating system, substantially as described.
- 45 3. A combined generator and radiator comprising a header, a partition which divides the interior thereof into compartments, pipes secured in said header the inner ends of which are in open communication with the interior of said header and the outer ends of which are closed, said pipes including generator and radiator pipes which communicate, respectively, with different compartments of said header, and open-ended pipes secured in the partition wall and which extend into the pipes secured in said header, the attached ends of which are in open communication with the compartments of the header other than those with which the pipes into which they extend, respectively, communicate, substantially as described.
5. A combined generator and radiator comprising a header comprising a substantially vertical leg and a substantially horizontal leg, a partition which divides the interior of said header into compartments, generator pipes secured in said header and which extend beneath the horizontal leg or section thereof and which communicate with one compartment of said header and radiator pipes secured in the horizontal section of said header, the inner ends of which communicate with the other compartment of said header and the outer ends of all of said pipes being closed, and open-ended pipes secured in the partition wall and which extend into the pipes secured in said header and which communicate with the compartment of the header other than those with which the outer pipes into which they extend, respectively, communicate, substantially as described.
- In testimony that I claim the foregoing as my invention, I affix my signature in the presence of two subscribing witnesses this 14th day of August, 1914.
